SAFETY RAZOR

Horace E. Ramsay, Oklahoma City, Okla., assignor of one-sixth to Wheeler H. Garrison and one-sixth to Ernest E. Yeck, both of Oklahoma City, Okla.

Application February 28, 1933, Serial No. 658,957

6 Claims. (Cl. 30—41)

My invention relates to a safety razor, and more particularly to a razor of the character mentioned which is provided with means whereby the blade may be thoroughly cleansed without removing it from the razor, and while the several parts of the razor and blade are in loosely assembled position.

The objects of my invention are to provide a device of this class which is new, novel, practical and of utility;

The invention further comprehends the provision of a safety razor constructed so as to permit the lower guard to revolve with respect or reference to the blade, together with means operative upon rotation of the lower guard for effecting a scraping of that face of the blade presented toward the revolving lower guard thereby to insure a thorough cleansing of the blade.

Another feature and object is that it expedites a thorough cleansing of the blade without requiring a disassembling of the razor therefor, and the consequent reassembling of the parts thereof for further, or future use.

It is a further object to provide a safety razor which may be readily cleansed after use and which will insure a positive and efficient removal of accumulation from the blade without requiring removal of the blade from the razor, and generally to improve upon known types of safety razors.

A further object is to produce a razor of the class described the parts of which may be easily, quickly, and readily disassembled and reassembled; which will be easily operated; which is simple; and yet durable; and which will be efficient in accomplishing all the objects and purposes for which it is intended.

Heretofore, some have claimed that the razor blade can be rinsed by loosening the parts of the razor sufficiently to permit the flexed blade to return to its normal plane contour and thus become spaced from the guard. However, in the type of razor blade under present construction the guards and blade revolving under action of the water during rinsing, very often become completely disassembled, whereas, in the present invention the possibility of the guard becoming completely separated from the handle is precluded.

With these and other objects in view as will more fully appear, my invention consists in the construction, novel features, and combination of parts hereinafter more fully described, pointed out in the claims hereto appended and illustrated

in the accompanying one sheet drawing, of which,

Figure 1 is a sectional elevational view of a safety razor embodying the features of the present invention, the blade being shown in its loosened position with relation to the lower guard of the razor;

Figure 2 is a bottom plan view of the upper guard;

Figure 3 is a top plan view of the lower guard;

Figure 4 is an end elevation of the upper guard;

Figure 5 is an end elevation of the lower guard;

Figure 6 is a transverse sectional view taken substantially on the line 6—6 of Figure 1; and

Figure 7 is a plan view showing the lower guard rotated approximately ninety degrees with relation to the upper guard.

Like characters of reference designate like parts in all the figures.

It is understood that various changes in the form, proportion, size, shape, weight, and other details of construction, within the scope of my invention, may be resorted to without departing from the spirit or broad principles of my invention and without sacrificing any of the advantages thereof; and it is also understood that the drawing is to be interpreted as being illustrative and not restrictive.

Referring now more particularly and in detail to the drawing, it will be seen the razor comprises a handle 5 which is open at its upper end, said handle 5 being preferably knurled, and is provided at its upper end with internal screw threads 6, and inwardly from said end with an internal shoulder 7. The guard of the razor comprises an upper or outer guard 8, and lower or inner guard 9. In the present instance means is provided for positively retaining the lower guard in a fixed clamped position between the upper guard 8 and the upper end of the handle 5 or in a loose position between said upper guard 8 and handle 5 for rotation relative thereto as desired, such means consisting of a stem 10 having an enlarged intermediate portion 15, the lower part 45 of which is coarsely threaded as at 11 for co-operation with the thread 6 of the handle 5 while the upper portion of the enlarged intermediate part of the stem is smooth, or non-threaded, as shown. The lower guard 9 is provided, intermediate its ends with a suitable opening for receiving the enlarged portion of the stem 10, and on the under side is provided with two slightly arcuate lugs 25 for providing better surface facility for the catching of the water in cleansing. 55

The upper guard 8 is provided with a finely threaded aperture 13, and on the under side of the guard 8 in line with the aperture said guard is provided with a boss 14 which is adapted to 5 abut the shoulder 15 formed by the enlarged intermediate portion of the stem 10 when the finely threaded end 4 of the stem 10 is screwed into the aperture 13 of said upper guard 8.

Said stem 10 extends from its finely threaded 10 end 4 through the handle 5 and out at its nether end, being opposite to the end whereon said guard is disposed. On its lower end said stem 10 is equipped preferably with a knurled knob 16 arranged to engage and co-act with a shoulder 17 15 adjacent said nether, or outer end of said handle 5, when the handle 5 is threaded downwardly to thereby limit movement of said handle 5 relative to the guard 8 when said handle is rotated in a counter-clockwise direction for loosening the 20 lower guard 9. Knob 16 and shoulder 17 thus provide interengaging means for preventing the complete removal of the handle 5 from the stem 10, as is apparent.

The blade to be clamped between the guards 8 25 and 9 is of the usual and conventional type of construction and is designated generally by the reference character 18. In the present instance the blade 18 is of a well known type of blade equipped with a longitudinal slot intersecting a 30 series of relatively spaced apertures, and is recessed or cut-away at each of the four outer corners, such type of blade being now commonly used.

To retain blade 18 against rotation relative to 35 guards 8 and 9, the upper guard 8 is provided on its under side with longitudinally extending ribs 19 projecting from relatively opposite sides of the boss 14 and these ribs 19 are provided at their free ends with depending lugs 20. At each 40 corner of the bottom side of the guard 8 said guard 8 is provided with a depending lug 24 for co-acting with the respective four outer corner cut-away portions of said blade member 18. The lower guard 9 on its top side is provided centrally 45 with longitudinally extending grooves 21 for accommodating the ribs 19 when the guards 8 and 9 are in their final position for clamping the blade 18 therebetween, it being understood that the ribs 19 extend through the slot of the blade and enter 50 the grooves 21 when the guards 8 and 9 are in their final blade-clamping position. Likewise, the lugs 20 extend through the openings provided in the blade 18 adjacent the ends of the referred to slot, and are received in arcuate transverse 55 notches or grooves 22 provided inwardly from the ends of the lower guard 9. Thus, with the ribs 19 fitting in the grooves 21, and the lugs 20 fitting in the arcuate grooves 22 the blade 18 will be secured against rotation relative to the guards 8 60 and 9 when the latter are in their full blade-clamping position. It will also be apparent that when the guards 8 and 9 are separated as shown in Figure 1, the ribs 19 and lugs 20 engaging the blade 18 in the manner above explained and depending lugs 24 co-acting with the cut-away corners of said blade 18 will retain said blade 18 65 against rotative movement relative to the guard 8.

The guard 9 has the longitudinal sides of its 70 grooves 21 rising above the plane of the top surface of the guard and beveled or otherwise formed to provide parallel scraping edges 23, which edges, as shown in Figure 5 have wiping engagement with a face of the blade 18 when the parts are in the position shown in Figure 1; thus it will be 75 seen that with the parts as shown in Figure 1

a rotation of the guard member 9 relative to the blade 18 and guard member 8 will cause the scraping edges 23 to move over the face of the blade and thereby remove any accumulations on said face of the blade 18.

The use and operation of the razor is thought to be apparent from the foregoing.

In assembling the parts, the stem 10 is first threaded inwardly of the handle 5, and the knob 16 attached. Next, the blade 18 is placed on the 10 guard 8, the ribs 19, lugs 20 and boss 14 being presented upwardly to pass through the slots and openings usually provided in the blade. Guard 9 is then placed on top of the blade 18 with the groove 21 receiving the ribs 19 and the grooves 22 15 receiving the lugs 20 while the boss 14 extends into the aperture of the lower guard 9. The end 4 of the stem 10 is then passed through the aperture in the guard 9 for co-operation with the threads 13 of guard 8 to secure the guard 8 on 20 said stem 10. Handle 5 is then rotated in a clockwise direction relative to the stem 10 to jam against the guard 9 and thereby clamp the blade 18 between the guards 8 and 9 with the parts as suggested in the drawing. Lugs 24 engage the 25 notched corners of the blade 18 as is apparent and the blade in its fully clamped position being flexed, whereupon the razor is ready for use.

After use, and for cleaning the razor, the handle 5 is reversely rotated for loosening the guard 30 9. The razor may be rinsed by placing it under a spigot and running the water thereover, whereupon guard 9 will be caused to rotate relative to the guard 8 and blade 18 with the ribs 23 scraping 35 one face of the blade 18 to thereby loosen and remove any accumulations on the blade. Perpendicular blades or wings 25 are provided beneath the guard 9 for expediting rotation of the guard by the running water.

Thus it will be seen that an effective rinsing 40 and cleansing of the razor and blade may be readily effected without requiring a complete disassembly of the parts.

Obviously the invention is susceptible of embodiment in forms other than that which is illustrated in the accompanying drawing and described herein, and is applicable for uses and purposes other than as detailed, and I therefore consider as my own all such modifications and adaptations and other uses of the form of the device herein described as fairly fall within the scope 45 of my invention.

Having thus described my invention, what is claimed and desired to be secured by Letters 50 Patent, is:

1. In a safety razor, an upper guard member, a lower guard member, a handle, a stem adapted to extend through an opening in the lower guard member and having screw threaded engagement 60 at one end with the upper guard member, and screw threaded engagement adjacent a relatively opposite end with said handle whereby said handle may be axially shifted relative to said stem for securing the lower guard member in clamped 65 or released position on said stem between said handle and said upper guard member, inter-engaging means on said stem and handle to prevent complete disengagement of the handle from said stem when the handle is moved in one direction to 70 release said lower guard member, said upper guard member provided on the under side thereof with longitudinally extending ribs and depending lugs at the ends of said ribs, said lower guard member being provided with longitudinally extending 75

grooves for receiving said ribs and with arcuate transverse grooves for receiving said lugs, the sides of said longitudinal grooves projecting above the plane of the upper face of said lower guard member for wiping engagement with a blade when the latter is loose between said guard members upon rotation of the lower guard member relative to the upper guard member.

2. A safety razor comprising an outer guard member or cap with an elongated stem, an inner guard member movable on the stem, a tubular handle telescoping the stem, said stem and said handle having threaded engagement whereby the guard members may be drawn together, and means for limiting the relative longitudinal movement of the handle and stem when they are threadedly disengaged, said means permitting the free rotation of the stem within the handle, the adjacent faces of the two guard members respectively provided with complementary male and female connections which are in registration when the guard members are aligned and drawn together, the female member provided with arcuate grooves for permitting independent complete rotation of both members when the members are slightly separated.

3. Organization as described in claim 2, in which the stem is removably connected to the outer guard member or cap.

4. In a safety razor, the combination with an outer guard member having a stem, and a handle threadedly connected to the stem, the nether surface of said guard member having projections, of an inner guard member upon the stem and movable with relation thereto, said inner guard member having indentations for receiving said projections when the two members are aligned and clamped together, and also having arcuate grooves for accommodating the projections and permitting relative independent complete rotative movement of said members when they are slightly separated.

5. Organization as described in claim 2, and wings carried by one of the guard members for expediting its rotation when the razor is held under a stream of running water.

6. Organization as described in claim 4, and wings carried by one of the guard members for expediting its rotation when the razor is held under a stream of running water.

HORACE E. RAMSAY.
